DESIGN.

No. 32,342.

Patented Mar. 13, 1900.

R. J. & F. WRIGHT.
CARPET STRETCHING PLATE.

(Application filed Feb. 13, 1900.)

UNITED STATES PATENT OFFICE.

ROBERT J. WRIGHT AND FRED WRIGHT, OF COLDWATER, MICHIGAN.

DESIGN FOR A CARPET-STRETCHING PLATE.

SPECIFICATION forming part of Design No. 32,342, dated March 13, 1900.

Application filed February 13, 1900. Serial No. 5,118. Term of patent 14 years.

To all whom it may concern:

Be it known that we, ROBERT J. WRIGHT and FRED WRIGHT, citizens of the United States, residing at Coldwater, in the county of Branch and State of Michigan, have invented and produced a new and original Design for a Carpet-Stretching Plate, of which the following is a specification.

This invention relates to a new and original design for a carpet-stretching plate, and has for its object to provide a design of this character which shall be both ornamental and useful.

The leading feature of the design resides in a flat plate having the substantially-circular opposite ends and an intermediate connecting web which is of less width than the diameter of either circular end.

Minor features of the design reside in the corrugated or undulated marginal edge of the plate, the laterally-deflected ears, which are arranged at the same edge of the plate and upon the respective circular ends thereof and having the central perforations, the plurality of concentrically-arranged circular series of pointed projections for each end of the plate, all of which projections incline toward the same edge of the plate which has the ears, the central circular perforations for each end of the plate, the circular series of elliptical perforations grouped concentrically about the respective circular perforations, each elliptical perforation being disposed radially with respect to the circular opening, the radially-disposed almond-shaped perforations grouped in a circular series about the elliptical perforations and having their pointed ends extending inwardly between adjacent elliptical perforations, the circular series of rectangular perforations, each of the latter being disposed between adjacent almond-shaped perforations and aligned radially with the adjacent elliptical perforation, the pairs of oppositely-bowed arcuate series of elliptical-shaped perforations which are disposed laterally of the web adjacent to the inner sides of the respective circular ends of the plate, the triangularly-related pointed projections grouped between the opposite pairs of the arcuate series of perforations and located at opposite longitudinal edges of the plate, and

the rectangular perforations located centrally with respect to the respective groups of triangularly-related projections.

In the drawings, Figure 1 is a perspective view of a carpet-stretching plate embodying the present design. Fig. 2 is a transverse sectional view, taken on the line *x-x* of Fig. 1.

Corresponding parts in both figures of the drawings are designated by like characters of reference.

Referring to the accompanying drawings, the numeral 1 designates the flat plate, having the substantially-circular ends 2 and the web 3, which is intermediate of and also connects the opposite circular ends.

The marginal edge of the entire plate is corrugated or undulated, as plainly shown in Fig. 1 of the drawings, and each circular end is provided with a laterally-deflected ear 4, having a central perforation 5, both ears being located at the same edge of the plate.

Each circular end has a central circular perforation 6, and grouped concentrically about each circular perforation is a plurality of series of pointed projections 7, all of which are inclined in the same direction toward the longitudinal edge of the plate which has the deflected ears.

Each end of the plate has a circular series of elliptical perforations 8, which are grouped concentrically about the central perforation 6, and each elliptical perforation being disposed radially with respect to the central perforation. Extending about the elliptical perforations is a concentric series of almond-shaped perforations 9, having their pointed ends extending radially inward between adjacent elliptical perforations. A concentric series of rectangular perforations 10 surround the several groups of perforations, and each rectangular perforation is located between adjacent almond-shaped perforations and aligned radially with the adjacent elliptical perforation.

Formed in the web and located intermediate of the circular ends of the plate are the pairs of oppositely-bowed arcuate series of elliptical perforations 11, which are disposed transversely of the plate, and between these series of perforations and at opposite sides of the plate are the groups of triangularly-re-

lated pointed projections 12. Located centrally with respect to the respective groups of triangularly-related projections are the rectangular perforations 13.

5 What we claim is--

The design for a carpet-stretching plate, as herein shown and described.

In testimony that we claim the foregoing as

our own we have hereto affixed our signatures in the presence of two witnesses.

ROBERT J. WRIGHT,
FRED WRIGHT.
